UNITED STATES PATENT OFFICE.

ALGERMONT H. WALDO, OF ST. PAUL, MINNESOTA.

DESIGN FOR A RUG.

57,406.

Specification for Design. Patented Mar. 15, 1921.

Application filed January 3, 1921. Serial No. 434,794. Term of patent 3½ years.

To all whom it may concern:

Be it known that I, ALGERMONT H. WALDO, a citizen of the United States, residing at St. Paul, in the county of Ramsey and State of Minnesota, have invented a new, original, and ornamental Design for a Rug, of which the following is a specification, reference being had to the accompanying drawing, forming a part thereof, and wherein—

The figure is a plan view of a rug showing my new design.

I claim:

The ornamental design for a rug, as shown.

Signed at St. Paul, Minnesota, December 29th, 1920.

ALGERMONT H. WALDO.

action in Design Letters Patent No
57,406.

It is hereby certified that Letters Patent No. 57,406, granted March 15, 1921, upon the application of Algermont H. Waldo, of St. Paul, Minnesota, for a Design for a "Rug," were erroneously issued to the inventor, said Waldo, whereas said Letters Patent should have been issued to Crex Carpet Company, of New York, N. Y., a Corporation of Delaware, as shown by the records of assignments in this office; and that the said Letters Patent should be read with this correction therein that the same may conform to the record of the case in the Patent Office.

Signed and sealed this 10th day of May, A. D., 1921.
